UNITED STATES PATENT OFFICE

DONALD E. SARGENT, OF JACKSON, MICHIGAN, ASSIGNOR TO WILLIAM & MATILDA SPARKS FOUNDATION, INC., OF JACKSON, MICHIGAN, A CORPORATION OF MICHIGAN

DESIGN FOR AN ARTIFICIAL CASCADE STAIRWAY

Application filed July 18, 1932. Serial No. 44,363. Term of patent 14 years.

To all whom it may concern:

Be it known that I, DONALD E. SARGENT, a citizen of the United States, residing at Jackson, in the county of Jackson and State of Michigan, have invented a new, original, and ornamental Design for an Artificial Cascade Stairway, of which the following is a specification thereof.

Fig. 1 is a perspective view of an artificial cascade stairway showing my new design.

Fig. 2 is a cross sectional view taken upon

line 2—2 of Fig. 1; the view being broken into two transposed sections on line 1—1.

Fig. 3 is a side elevational view of Fig. 1 taken upon a larger scale than Fig. 2 for clarity; the view being broken into three transposed sections on lines 1—1 and 2—2.

I claim:

The ornamental design for an artificial cascade stairway as shown and described.

DONALD E. SARGENT.
